(57) **CLAIM**

The ornamental design for solar module assembly, as shown and described.

DESCRIPTION

FIG. 1 is a perspective view of a solar module assembly according to the embodiment of the present invention.

FIG. 2 is a top view of the solar module assembly in FIG. 1. FIG. 3 is a bottom view of the solar module assembly in FIG. 1.

FIG. 4 is a front end view of the solar module assembly in FIG. 1.

FIG. 5 is a back end view of the solar module assembly in FIG. 1.

FIG. 6 is a right side view of the solar module assembly in FIG. 1; and,

FIG. 7 is a left side view of the solar module assembly in FIG. 1.

The broken lines shown represent unclaimed subject matter and form no part of the claimed design.
